UNITED STATES PATENT OFFICE.

J. FAIRFIELD CARPENTER, OF BERLIN, GERMANY.

VALVE FOR ELECTRO-PNEUMATIC RAILROAD-BRAKES.

SPECIFICATION forming part of Letters Patent No. 378,658, dated February 28, 1888.

Application filed September 12, 1887. Serial No. 249,518. (No model.)

To all whom it may concern:

Be it known that I, J. FAIRFIELD CARPENTER, a citizen of the United States, residing at Berlin, Prussia, Germany, have invented a 5 certain new and useful Improvement in Valves for Electro-Pneumatic Railroad-Brakes, of which the following is a full, clear, and exact description.

The object of this invention is to provide a 10 valve mechanism for pneumatic railway-brakes which may be operated electro-pneumatically to apply and release the brakes, or may be operated pneumatically alone for the same purpose. This valve mechanism is 15 designed to be operated either by means of an electric current which acts upon supplemental valves to cause a reduction of air-pressure in the valve-box only, (the air-pressure in the main pipe being unaffected,) thereby causing 20 the brakes to act in the usual way, or the valve mechanism may be operated solely by variations of the air-pressure in the main pipe, which is used to convey the air to the ordinary auxiliary reservoirs under each car in a train 25 of cars.

The invention is herein set forth as constructed for use in those systems of air-brakes which comprise air-compressing apparatus and a main reservoir on the locomotive, air-pipes 30 leading therefrom to the auxiliary reservoirs under each car, a brake-cylinder under each car, and a valve interposed between the brake-cylinder, reservoir, and main pipe; and inasmuch as said systems are well known and in 35 common use, no further description thereof is deemed necessary herein.

Stated in very broad and general terms, the invention consists in a valve mechanism constructed and arranged substantially as herein 40 after particularly set forth and claimed, and adapted to be operated either electro-pneumatically or pneumatically to operate the brakes.

In the accompanying drawings, in the several figures of which like parts are similarly designated, Figure 1 is a vertical section of the valve mechanism, one piston-head and one magnet-box being shown in elevation. Fig. 2 is a transverse section. Fig. 3 is a horizontal 45 section, both of the piston-heads being shown in elevation, excepting that part of the piston

B' is broken away to show a leak-hole; Fig. 3^a, details of the piston d and valves e d' detached. Fig. 4 is a section similar to Fig. 1 with the valve in position for applying the brakes. 55 Figs. 5 and 6 are longitudinal and transverse sections of a modification.

A is the valve box or case.

B and B' are pistons rigidly arranged upon a connecting-stem, B². 6c

C is a slide-valve rigidly affixed upon the stem B² between the pistons.

D D' are electro-magnets arranged in cases secured to the valve-box A. Each electro-magnet is provided with an armature, E, which 65 is secured to a stem, E', the upper end of which is provided with a valve, F, the said valve having its seat in the upper end of the tubular portion E². The armature E is normally pressed from the electro-magnet by a spring, 70 E³, and this spring at the same time serves to normally seat the valve F. Conductors G G' are connected with the magnets D D', respectively.

The valve mechanism is connected to the 75 main pipe by the passage a, and a port, b, leads to a chamber, H, on one end of the valve-box, and this chamber is separated from the main valve-chamber by the wall b', in which is arranged an opening provided with a check-valve, c. Within the chamber H is arranged 80 a piston, d, which is provided with a check-valve, d', covering a central port or opening in the said piston. d² is a compartment in the chamber H. Springs d³ and d⁴ are arranged 85 within the chamber H, and bear, respectively, upon the check-valves c and d'. The valve-box is divided into chambers e, f, and f², and the chambers f and f² communicate through a leak-hole, f', in the pistons B'. A passage or 90 port, g, serves to connect the valve-case and the auxiliary reservoir, and the said passage or port opens into the valve-case in the chamber f—that is to say, between the pistons B and B'.

A passage or port, h, serves as the 95 means of communication between the brake-cylinder and the valve, and an exhaust-port, i, is arranged in the valve case or box and communicates with the brake-cylinder through the port h and the ports k in the slide-valve C. 100 The chamber e communicates with the external atmosphere through the ports l m and the

tubular post E², and a similar communication of the chamber f² is had through the port l' and other openings in the electro-magnet chamber D'. I may here remark that the valve 5 F and the similar valve in the electro-magnet D' are herein referred to as "supplemental" valves. A weighted check-valve, x, is interposed between the inlet a and the chamber f. A leak-hole, n, is arranged in the wall b'. A 10 spring, o, is interposed between the piston B and the wall b'.

The construction and arrangement of parts being substantially as herein indicated, I will now proceed to describe the operation.

15 Air from the main pipe, entering at a, passes thence through the passage b into the chamber H and on the right-hand side of the piston-valve d. This has the effect of moving the said piston toward the left, and the check- 20 valves c and d' being connected, and the said check-valve d' being seated on the left-hand side of the said piston d, the said valve c will be opened, thereby admitting the air from the said valve c into the chamber e. This will 25 have the effect of driving the pistons B B', together with the slide-valve C, into the position shown in Figs. 1 and 3. The valve x is weighted to about fifteen pounds pressure, and hence will be opened to admit air into the chamber f only 30 when that pressure is overcome, which it will be by the incoming air fresh from the main reservoir at the locomotive. The air passes from the chamber f through the port g to the auxiliary reservoir. In this position the brakes are 35 "off." Now, if the electro-magnet D be energized, its armature E will be lifted, and thus the valve F will be opened. The result is that the air in the chamber e is free to escape through the ports l and m and past the valve F into the atmosphere. This will leave an excess of pressure 40 in the chambers f and f² and the communicating auxiliary reservoir, whereby the pistons B B' will be moved to carry the slide-valve C past the port h, thereby closing the 45 exhaust-port and allowing the air to pass from the auxiliary reservoir through the port h to the cylinder and apply the brakes. The chamber e cannot be refilled from the main pipe during this operation, because the valve c will 50 be closed by its pressure, the small leak-hole not being able to overcome the waste at the open valve F. When the brake has been applied with sufficient force, the electric current is cut off from the magnet D, whereby its armature E drops and closes the valve F. Air 55 pressure from the main pipe will then enter the chamber e through the small leak-hole n, and, equilibrium being thus restored on all sides of the pistons B B', the spiral spring o 60 will force the said pistons, together with the slide-valve C, into an intermediate return position, where further flow of air from the auxiliary reservoir to the cylinder through the port h is cut off. In this position the brakes 65 can be held on as long as desired.

To release the brakes, an electric current is sent through the other conductor, G', energiz-

ing the magnet D', lifting its armature, and opening its supplemental valve, and thus exhausting into the atmosphere through the port 70 l', the chamber f² back of the piston B', and causing the pistons B B', and with them the slide-valve C, to complete the stroke to the right and obtain the position shown in Figs. 1, 2, and 3 of the drawings, in which position, 75 it will be observed, the brake-cylinder is open to the external atmosphere through the ports h k i, thus releasing the brakes. Now, when the electric current through the conductor G' is cut off, equilibrium is again restored through 80 the small leak-hole f' and the valve mechanism remains in the released position shown.

To work the valves by means of variations of air-pressure in the main air-pipe alone, instead of in conjunction with electricity, I proceed as follows: Air is first charged through the valves into the auxiliary reservoir the same as before. To apply the brake, the air-pressure in the main pipe is suddenly reduced. The check-valve x thus becomes operative to prevent the return flow of air from the chamber f and auxiliary reservoir to the main pipe, and at the same time, the pressure being thus suddenly taken off the piston d and its valve c, the pressure in the 95 chamber e will open the said valve c, and the air in said chamber thus escape through said valve and the port back into the main pipe. This will destroy the equilibrium of the pistons B B', and hence said pistons and the slide-valve C will be moved over to the left, as before, uncovering the port h and permitting the flow of air from the auxiliary reservoir to the brake-cylinder and applying the brakes. When the air passes from the reservoir to the 105 cylinder in putting on the brakes, (by air,) the pressure in the auxiliary reservoir will naturally be reducing itself until it reaches a point at or below that of the main pipe which had previously been reduced by letting out air to 110 put on the brakes. This is the "point of equilibrium," where pressures are equal in the pipe and in the reservoir, and the spring o will act to move the valve C into position to cut off further supply of air to the brake-cylinder. To release the brakes, the air-pressure in the main pipe is suddenly raised, and the air, passing through port b and into the chamber H, will again push back the piston d, thereby raising the valve c and recharging the 120 chamber e with a higher pressure, which will effect the completion of the return-stroke of pistons B B' and slide-valve C into the released position shown, thereby exhausting the brake-cylinder through the ports h k i. To 125 accomplish satisfactorily these double functions—that is to say, working the valve electro-pneumatically or simply pneumatically—by means of one and the same valve mechanism, it is necessary to automatically open and close the connection between the main pipe and the chamber e, for in working the brake electrically the chamber e must be emptied rapidly 130 through the comparatively small valve F, and

a large communication with the main pipe cannot, therefore, be allowed; but in working the brake pneumatically a large free communication between the main pipe and chamber 5 *e* is absolutely necessary in order to insure quick application and release. The arrangement of the valves *c* and *d'* and piston *d*, however, permits this to be accomplished, for it has been shown that the valve *c* remains closed 10 while applying the brakes by means of electricity, but that it is opened when applying and releasing the brakes pneumatically. It should be here remarked that any air-pressure which may leak past the piston *d* into the 15 compartment *d'* of the chamber *H* is removed when working the brakes by air, for as soon as the pressure at *b* is reduced the piston *d* will move to the right, thus opening its valve *d'* and permitting the excess of pressure from 20 behind to pass through the opening in the piston *d* with which the valve *d'* co-operates, and thence escape out through port *b*.

In Figs. 5 and 6 I have shown a modification of the invention which differs more in arrangement than in aught else, excepting that 25 I employ a common three-way stop-cock, *P*, leading to the check-valve *c*, as a substitute for the valvular apparatus shown in the chamber *H* of the other figures.

30 As a mechanical equivalent for the pistons shown in Figs. 1, 2, 3, and 4, and a full substitute in purpose, effect, and operation therefor, I have shown in Figs. 5 and 6 flexible diaphragms united by a common stem, as are 35 the pistons before referred to; but instead of having the leak-hole *n* in the wall *b'*, I make said leak-hole of right-angular outline in one end of the stem, and, instead of having a leak-hole, *f'*, in the diaphragm, I arrange it of similar outline in the opposite end of said stem. 40

As will hereinafter more particularly appear, the stop-cock *P* is not automatic, but is to be operated by hand in changing from the pneumatic to the electric working of the brake.

45 In electrically working the valve shown in Figs 5 and 6 the stop-cock *P* is turned into the position shown, so that air from the main pipe passes through the port *v* to the check-valves *x* and *c*. At the same time there is 50 cut off by this plug the port *b'*, which leads to the chamber *e*, so that air from the main pipe can only reach the chamber *e* through the small leak-hole *n*, Fig. 5.

To work the brake pneumatically, the plug *P* is given a half-turn, so as to open both the 55 ports *b* and *b'*, and then the chamber *e* will have a large communication with the main pipe through the port *b'* without passing the check-valves *c* or *x*.

In the claims hereinafter made, although I 60 have used the word "piston" to apply to the devices *B* and *B'*, I wish to be understood as including in said term the diaphragms shown in the modification; and so, also, in reference to the device interposed between the thus- 65 qualified piston and the main pipe, I have used the generic term "valve," and in said term I desire to be understood as including the stop-cock *P*, inasmuch as such stop-cock is simply one form of valve.

70 What I claim is—

1. An electro - pneumatic railway - brake valve mechanism, comprising a valve-box, a double piston arranged therein, a slide-valve operated by the said piston and controlling 75 communication between the auxiliary reservoir, brake-cylinder, and atmosphere, a valve interposed between the main pipe and one end of this double piston, and an electric valve controlling communication of the chamber be- 80 tween the last-named valve and piston and the atmosphere, substantially as set forth.

2. A valve for pneumatic railway-brake systems, comprising a valve-box, a double piston arranged in said valve-box, a slide-valve connected to said double piston and controlling communication between the auxiliary reservoir, brake-cylinder, and atmosphere, and a compound piston - valve interposed between one end of said double piston and the main air- 90 pipe, and adapted to admit air into the valve-box between itself and said end of the double piston to operate the said double piston and slide-valve to release the brakes, and also operable by a reduction of pressure of the main 95 air-pipe to exhaust the air from the aforesaid chamber, and thereby permit the movement of the double piston in the opposite direction to apply the brakes, substantially as set forth.

In testimony whereof I have hereunto set 100 my hand this 6th day of September, A. D. 1887.

J. FAIRFIELD CARPENTER.
